R. TANNER

PROPELLING MEANS

Filed July 17, 1924

Poe Tanner, Inventor

By *C. Snow & Co.*

Attorneys

UNITED STATES PATENT OFFICE.

ROE TANNER, OF ATTICA, OHIO.

PROPELLING MEANS.

Application filed July 17, 1924. Serial No. 726,557.

To all whom it may concern:

Be it known that I, ROE TANNER, a citizen of the United States, residing at Attica, in the county of Seneca and State of Ohio, 5 have invented a new and useful Propelling Means, of which the following is a specification.

This invention relates to aeroplane propelling means and aims to provide a novel 10 means whereby a propeller at the forward end of a machine and a propeller at the rear end of the machine may be simultaneously operated in opposite directions, the pitches of the blades of the propellers being such as 15 to produce an equal amount of torque to the body portion of the machine, thereby stabilizing the machine.

Another important object of the invention is to direct the power to the propellers in 20 such a way that the propellers will adjust themselves to give an equal thrust, when in operation.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed, may be made within the scope of what is claimed, without departing from the spirit of the invention.

Referring to the drawing:

Figure 1 illustrates a side elevational view 35 of an aeroplane supplied with propelling means constructed in accordance with the present invention.

Figure 2 is a fragmental sectional view 40 through the gearing employed for transmitting power from one shaft to the adjacent shaft.

Figure 3 is an elevational view of the inner supporting ring of the gearing.

Referring to the drawing in detail, the 45 reference character 5 designates the body portion of an aeroplane and the reference character 6 designates the power plant of the machine.

The forward propeller is indicated at 7 50 and is mounted on the forward extremity of the shaft 8 which carries a pinion 9 at its rear end meshing with the pinion 10, which pinions are mounted in the gear housing 11.

A shaft 12 extends through the gear housing 55 11 and carries a beveled pinion 13 which

pinion is in mesh with the beveled pinions 14 carried by the spider 15, there being provided a sectional supporting ring 16 to which the shafts 17 of the spider extend.

Formed on the ring 16 are teeth 18 over 60 which operates the chain 19, the chain also operating over pinion 20 carried at one end of the crank shaft 21 of the engine 6, so that movement of the crank shaft will result in a relative movement of the spider to rotate 65 the pinions associated therewith.

The rear propeller shaft is indicated at 22 and carries a propeller 23, the pitch of the blades of the propeller 23 being the reverse 70 of the pitch of the blades of the propeller 7 so that as the propellers are rotating in opposite directions, both propellers will be acting to move the machine in a common direction.

Mounted on the forward end of the propeller shaft 22 is a beveled pinion 24 which is in mesh with the beveled pinions 14 so that movement will be transmitted to the shaft 22.

From the foregoing it will be obvious that 80 due to the pitches of the propeller blades, the action of the propellers 7 and 23 will be to move the aeroplane forwardly when the power plant is put into motion.

From the foregoing it will be obvious that 85 the propeller at the rear of the machine and which operates under less resistance than the forward propeller, will operate at a greater speed and due to the construction as shown and described, the propellers will adjust 90 themselves automatically, and give equal thrust.

While I have shown and described the device for use in connection with boats or the like, it is to be understood that the structure 95 may be efficiently employed on motor vehicles or the like, without departing from the spirit of the invention.

I claim:

A propelling mechanism for aeroplanes 100 including a power plant, a shaft extending through the power plant, said shaft carrying a propeller on one end thereof, a gear on the opposite end thereof, a gear housing housing the gear, a gear meshing with the first mentioned gear, a shaft on which the last mentioned gear is supported, said last mentioned shaft carrying a beveled pinion, a bearing adapted to rotate within the gear housing, 105 pinions carried by the bearing member and 110

adapted to mesh with the first mentioned member to receive motion therefrom, a shaft carrying a pinion at its forward end and disposed within the gear housing, and meshing with pinions carried by the bearing member, and a propeller on one end of the propeller shaft.

In testimony that I claim the foregoing as my own, I have hereto affixed my signature in the presence of two witnesses.

ROE TANNER.

Witnesses:

GEO. W. FINK,
H. G. HEDDEN.
